UNITED STATES PATENT OFFICE.

JAMES HUTCHISON, OF NEWARK, ASSIGNOR TO LINCOLN D. FARR, OF CAMDEN, NEW JERSEY.

DESIGN FOR OIL-CLOTHS.

Specification forming part of Design No. 9,889, dated April 3, 1877; application filed February 20, 1877.
[Term of Patent 3½ years.]

To all whom it may concern:

Be it known that I, JAMES HUTCHISON, of Newark, Essex county, State of New Jersey, have invented a new and Improved Design for Oil-Cloths, reference being made to the accompanying photographic illustration, making part of this specification.

What I claim as new, and desire to secure by Letters Patent, is—
The design for oil-cloths, as shown.

JAMES HUTCHISON.
